UNITED STATES PATENT OFFICE

FRANCIS B. RILEY, OF NEWTON, MASSACHUSETTS

DESIGN FOR A WOVEN OPEN FABRIC OF NONFLACCID STRANDS

Application filed June 15, 1928. Serial No. 27,151. Term of patent 3½ years.

To all whom it may concern:

Be it known that I, FRANCIS B. RILEY, a citizen of the United States, residing at Newton, in the county of Middlesex, and Commonwealth of Massachusetts, have invented a new, original, and ornamental Design for a Woven Open Fabric of Nonflaccid Strands, of which the following is a specification, reference being had therein to the accompanying drawing.

The accompanying drawing illustrates a plan view of a fabric embodying my new design.

I claim:

The ornamental design for a woven open fabric of nonflaccid strands substantially as shown.

FRANCIS B. RILEY.
